B. ZSARNAY,
MECHANICAL MOVEMENT,
ORIGINAL FILED FEB. 26, 1921.

Bela Zsarnay
By his Attorney
George C. Heinricke

UNITED STATES PATENT OFFICE.

BELA ZSARNAY, OF BELLEVILLE, NEW JERSEY, ASSIGNOR OF ONE-HALF TO
ABRAHAM LEWIS, OF NEWARK, NEW JERSEY.

MECHANICAL MOVEMENT.

Original application filed February 26, 1921, Serial No. 447,957. Patent No. 1,397,195. Divided and this application filed August 23, 1921. Serial No. 494,552.

To all whom it may concern:

Be it known that I, BELA ZSARNAY, a citizen of Hungary, residing at Belleville, county of Essex, and State of New Jersey, have invented certain new and useful Improvements in Mechanical Movements, of which the following is a specification.

This invention relates to a fan attachment or the adaptation of my mechanical movement described in my co-pending application No. 447,957, filed Feb. 21st, 1921, of which this is a division.

It is the principal object of my invention to use my above mentioned mechanical movement in connection with a rocking chair to drive fans during the rocking of the chair and for operating toy figures sitting on the chair.

These and other objects of the invention will become apparent as the description thereof proceeds, and will then be more particularly pointed out in the appended claim.

In the accompanying drawings, forming a material part of my invention, and in which:

Figure 1 is a side view of a rocking chair equipped with a device constructed according to the present invention.

Figure 2 is a front view thereof.

In the drawing the application of my movement to a rocking chair is illustrated.

The flat springs 41 are slightly curved and secured in approximately their middle as at 42 to the under faces of the rocker bars 42 which carry in the customary manner the seat 44, back rest 45, and arm rests 46 of the rocking chair. Near the ends the springs 41 carry pins 45 adapted to be secured in sockets at the lower ends of links 46 the

upper ends of which are pivotally secured to the outer faces of pulley wheels 47 on the outer ends of crank shafts 48 journaled in the upper part of the bars 43. Uprights 49 are secured at their lower ends to the seat 44 and arm rests 46 of the rocker and are forked at their upper ends to carry between the prongs 50 of the forks, stub shafts 51 on which are secured pulley wheels 52. The inner ends of the stub shafts 51 carry fans 53 and cables or ropes 54 are guided over the pulley wheels 52 and the pulley wheels 47.

From the foregoing description it will be clear that upon the rocking of the chair the springs 41 will be moved to operate through links 46, the pulley wheels 47 and through the intermediary of the cables 54, the fan 53 will be rotated.

What I claim is:—

In a rocking chair of the class described, a pair of rocker bars, flat curved springs secured to the under faces of said rocker bars, pins on said springs near the ends thereof, links provided with sockets at their lower ends adapted to receive the pins of said springs, forked uprights on said chair, crank shafts on said rocker bars, pulleys on said crank shafts to which the upper ends of said links are secured, stub shafts between the forked ends of said uprights, pulley wheels and fans on said stub shafts and cables guided over the pulleys on said crank shafts and over the last named pulley for transforming the motion of said rocker bars as a rotary motion to said fans, substantially as described.

In testimony whereof I have affixed my signature.

BELA ZSARNAY.
